(57) **CLAIM**

We claim, the ornamental design for a twin beam headlight, as shown and described.

DESCRIPTION

FIG. 1 is a front elevational view of a twin beam headlight in accordance with the new design, showing a break indicating a tubular detail of no particular length;

FIG. 2 is a side elevational view thereof;

FIG. 3 is a side elevational view from the opposite side shown in FIG. 2;

FIG. 4 is a rear elevational view thereof; and,

FIG. 5 is a top plan view thereof.
